(57) **CLAIM**

The ornamental design for a stool, as shown and described.

DESCRIPTION

FIG. 1 is a top, front, right perspective view of a first embodiment of a stool embodying our new design;

FIG. 2 is a front elevational view thereof, the rear elevational view, the right side elevational view and the left side elevational view being identical to the front elevational view of FIG. 2;

FIG. 3 is a top plan view thereof;

FIG. 4 is a bottom plan view thereof;

FIG. 5 is a top, front, right perspective view of a second embodiment of a stool embodying our new design, the top plan view thereof being identical to the view of FIG. 2, and the bottom plan view thereof being identical to the view of FIG. 4;

FIG. 6 is a front elevational view thereof, the rear elevational view, the right side elevational view and the left side elevational view being identical to the front elevational view of FIG. 6;

FIG. 7 is a top, front, right perspective view of a third embodiment of a stool embodying our new design, the top plan view thereof being identical to the view of FIG. 2, and the bottom plan view thereof being identical to the view of FIG. 4; and,

FIG. 8 is a front elevational view thereof, the rear elevational view, the right side elevational view and the left side elevational view being identical to the front elevational view of FIG. 8.

The broken line representations of support feet in FIGS. 1-8, and of chair structure in FIGS. 2, 4, 6, and 8 are for the purpose of illustration only, and form no part of the claimed design.
